United States Patent Office

Des. 218,365
Patented Aug. 11, 1970

218,365

VERTICAL TAKE-OFF FLYING MACHINE

John W. Sherwood, Atlantic, Iowa (202 NE. 3rd Panora,
Iowa 50216), and John W. Sherwood III, Rte. 3, Box
158, Guthrie Center, Iowa 50115

Original design application Apr. 3, 1967, Ser. No.
6,500. Divided and this application Sept. 16, 1968,
Ser. No. 13,538

Term of patent 14 years

Int. Cl. D12—07

U.S. Cl. D71—1

FIG. 1

FIG. 2

FIG. 3

FIG. 4

FIG. 5

FIG. 1 is a perspective view showing the new design for our vertical take-off flying machine.

FIG. 2 is a top plan view thereof.

FIG. 3 is a side view thereof.

FIG. 4 is a bottom plan view thereof, and

FIG. 5 is a front elevational view thereof.

This is a continuation-in-part of design application Ser. No. D. 6,500, filed Apr. 3, 1967, now abandoned. We claim:

The ornamental design for a vertical take-off flying machine, as shown.
